Inventor,
WILLIAM LE GRAND HAMILTON

By George P. Scull
Attorney

UNITED STATES PATENT OFFICE.

WILLIAM LE GRAND HAMILTON, OF TOTTENVILLE, NEW YORK.

ENVELOP.

1,306,061.

Specification of Letters Patent. Patented June 10, 1919.

Application filed December 13, 1918. Serial No. 266,531.

To all whom it may concern:

Be it known that I, WILLIAM LE GRAND HAMILTON, a citizen of the United States, and a resident of Tottenville, county of Richmond, State of New York, have invented certain new and useful Improvements in Envelops, of which the following is a specification.

My invention relates to envelops designed to be readily opened without injury to the contents.

One of the objects of my invention is to provide an envelop which shall be so constructed that the recipient may readily open the same with any paper cutter of the usual type without injury to the contents of the envelop, especially when the envelop is of the window type, in which case the contents, by reason of the peculiar folding of letters, are peculiarly subject to injury when the letter is opened in the usual manner by inserting a cutter under the top flap. Another object of my invention is to provide such an envelop with a visible marking so as to indicate to the recipient where the envelop is to be opened. With this and other objects in view my invention consists of certain novel features of construction, combination and arrangement of parts, as will be more fully described and pointed out in the appended claims.

In the drawings Figure 1 represents a back view of a type of envelop which I have chosen for purposes of illustration of my invention.

Fig. 2 is an enlarged cross-section on the line 2--2 of Fig. 1.

The corresponding parts are referred to both in the drawings and in the specification by similar reference characters.

In the drawings 10 represents the top flap of an envelop of the usual type, 11 the bottom flap, and 12 and 13 the two end flaps of such an envelop.

These flaps are folded and cemented together in the usual way, the top flap 10 being provided with cement to be used to seal the envelop, all as is well understood. The bottom flap overlaps a portion of the end flap 12 in the usual manner, and also in the usual manner a strip of cement is applied between these two flaps. In order to provide a ready means by which a cutter may be

inserted so as to cut or tear open the envelop without injury to the contents, I provide a space 15 between the two flaps, at which place the cement is omitted. Also, in order to provide easy access to the under cemented portion, as well as to indicate visually the point at which the cutter is to be inserted, I preferably notch the edge of the bottom flap 11, as at 16, this notch being formed in any convenient way, and not necessarily in the form indicated in the drawings.

In use the recipient of the envelop inserts a cutter into the opening 15 and cuts through the bottom flap 11 along the bottom of the envelop so that the contents may be readily removed. By placing the opening 15 away from the edges of the envelop I insure that the cutter does not enter the fold in the usual manner, and by providing the opening 15 at the bottom of the envelop instead of at the top, I also insure that the fold in the letter inclosed in envelops of the window type, which fold is usually at the top of the envelop, is not disturbed by the cutter.

By my improvement, therefore, I have provided a cheap and effective means by which envelopes may be opened without injury to their contents. It will be understood that the exact location of the opening 15 is not necessarily that indicated in the drawings. It may be near the edges of the envelop, although preferably I locate it in the position shown so as to have the cutter well above the fold of the letter. It will also be understood that the notch 16 is not essential. While I have indicated the opening 15 at one end of the envelop only, it will be understood that, if desired, this opening may be duplicated at the opposite end of the envelop as well.

I claim:

1. An envelop having bottom and end flaps with overlapping portions permanently cemented together and a top flap adapted to be sealed to the other flaps when the envelop is closed, the envelop having a small unobstructed opening between the bottom flap and one of the end flaps spaced a substantial distance from the lower edge, whereby a cutter inserted in said opening engages the outside of the contents of the envelop.

2. An envelop having bottom and end flaps with overlapping portions permanently cemented together and a top flap adapted to be sealed to the other flaps when the envelop is closed, the envelop having a small unobstructed opening between the bottom flap and one of the end flaps spaced a substan-

tial distance from the lower edge, whereby a cutter inserted in said opening engages the outside of the contents of the envelop, and 10 the edge of the uppermost flap being notched at said opening.

WILLIAM LE GRAND HAMILTON.
